UNITED STATES PATENT OFFICE.

QUEENE ELEANOR MARRS, OF KILLEEN, TEXAS.

COMBINED THIMBLE AND THREAD CUTTER.

Application filed August 23, 1922. Serial No. 583,749.

To all whom it may concern:

Be it known that I, QUEENE ELEANOR MARRS, a citizen of the United States of America, and a resident of Killeen, in the 5 county of Bell and State of Texas, have invented a new and Improved Combined Thimble and Thread Cutter, of which the following is a description.

My invention relates to a thimble having 10 means to sever a thread and more particularly the invention relates to a thimble having a cutter arranged in a novel manner in a depression produced in the end of the thimble and of novel form.

15 The general object of the invention is to provide a thimble having a depression so that the thimble end presents a transverse slot in which the cutter is arranged and formed in a manner to afford accommodation 20 for a cutter ample for its purpose, and presenting an entrance to the slot so narrow that thread will not be liable to accidentally find its way into the depression, the small entrance to the depression furthermore 25 serving to minimize the possibility of the needle entering therein.

Reference is to be had to the accompanying drawings forming a part of this specification.

30 Figure 1 is a longitudinal section as indicated by the line 1—1, Figure 3;

Figure 2 is a section at right angles to Figure 1 as indicated by the line 2—2 in said Figure 1;

35 Figure 3 is a front end view of the thimble;

Figure 4 is a fragmentary section as indicated by the line 4—4, Figure 5, the view showing a modification;

40 Figure 5 is a view at right angles to Figure 4.

Referring at first to Figures 1 to 3 the thimble 10 has a depression 12 formed in the front end 11 of the thimble, said depression extending across from side to side, thereby producing a slot 13 which is dovetail, the slot by reason of the depression 12 flaring downwardly toward the bottom. A cutter 14 is provided in the bottom of the depression 12 and extends transverse to the slot 13. 45 50

The entrance to the slot 13 is comparatively narrow with a view of the thread finding entrance thereto only when it is desired to sever the thread.

In Figures 4 and 5 the thimble 10^a has a 55 depression 12^a in the front 11^a, thereby producing a slot 13^a corresponding essentially with the slot 13 being flaring toward the bottom and narrow at the entrance. The cutter 14^a is produced in the form shown in Figures 4 and 5 integral with the material of the thimble instead of a separate cutter element 14 as in the first-described construction. 60

I would state in conclusion that while the 65 illustrated example constitutes a practical embodiment of my invention, I do not limit myself strictly to the exact details herein illustrated, since, manifestly, the same can be considerably varied without departure 70 from the spirit of the invention as defined in the appended claim.

Having thus described my invention, I claim:

As a new article of manufacture, a thimble 75 having a depression in the end thereof forming a slot, the depression flaring toward the bottom thereby presenting a narrow entrance to the slot, and a cutter in said slot transverse to the latter.

QUEENE ELEANOR MARRS.
